UNITED STATES PATENT OFFICE.

EDWARD A. LANGENBACH, OF CANTON, OHIO.

DESIGN FOR A BORDER-PLATE.

SPECIFICATION forming part of Design No. 26,241, dated November 3, 1896.

Application filed September 23, 1896. Serial No. 606,780. Term of patent 7 years.

To all whom it may concern:

Be it known that I, EDWARD A. LANGENBACH, a citizen of the United States, and a resident of Canton, county of Stark, State of Ohio, have invented and produced a new and useful Design for Metallic Border-Plates, of which the following is a full, clear, and exact description, reference being had to the accompanying drawings, making part of this specification.

The invention relates to a new design for metallic borders; and it consists of a plate of the configuration and ornamentation shown in the accompanying drawings, in which—

Figure 1 is a plan view of the new design for a metallic border, and Fig. 2 is a vertical sectional view of the same.

The leading feature of the design is a plate A, having its central portion curved inward or concaved, as shown at 1, thence extending upwardly a short distance, as shown at 2, then curved to produce the rib 3, then curved on a larger arc of a circle to produce the bulge 4, then concaved, as shown at 5, thence ver-

tically, as shown at 6, and thence laterally inward, as shown at 7. At the lower edge of the central portion 1 the plate extends vertically, as shown at 8, formed with two parallel ribs 9 and 10, and thence extends outward, as shown at 11. The rib 10 is provided with alternating circular and elongated balls 12 and 13, respectively, the circular balls being arranged in pairs. The central concaved portion is provided with wedge-shaped figures 14, the tops of which are curved, and alternating with these wedge-shaped figures 14 are leaves 15, and above the leaves are the convex semi-elliptical figures or swells 16.

What I claim is—

The design for a metallic border as herein shown and described.

In testimony whereof I have hereunto set my hand this 30th day of July, A. D. 1896.

EDWARD A. LANGENBACH.
